ROOF CONSTRUCTION FOR RAILWAY CARS

Alfred C. Lohse, Michigan City, Ind., and William H. Mussey, deceased, late of Chicago, Ill., by Carrie S. Mussey, executrix, Chicago, Ill., assignors to Pullman-Standard Car Manufacturing Company, Chicago, Ill., a corporation of Delaware

Original application March 29, 1937, Serial No. 133,632. Divided and this application February 28, 1941, Serial No. 381,151

3 Claims. (Cl. 105—404)

This invention relates to roofs for railway cars and more particularly to the roof construction and mechanism for securing the roof on the car.

One of the principal objects of the invention is the provision of a new and improved roof construction comprising a plurality of sheet metal plates having the carlines integral with the plates, together with reinforcing members for the carlines, the parts being so constructed and arranged as to form a roof that is cambered transversely of the car and that is adequately reinforced when in position on the car.

Another object of the invention is the provision of new and improved means for attaching a prefabricated roof structure in position on the longitudinal and transverse framing members of a railway car.

A further object of the invention is the provision of a new and improved car roof construction built up from sheet metal plates and that is comparatively inexpensive to fabricate, is light in weight and has a maximum resistance to stresses and distortion.

Other and further objects and advantages of the invention will appear from the following description taken in connection with the accompanying drawings, in which

Fig. 1 is a top plan view of a car embodying the invention, with parts broken away and parts in section;

Fig. 2 is a side elevation of the car showing the roof in position thereon, shown more or less diagrammatically and with parts broken away;

Fig. 3 is an end elevation of the upper portion of a car with the improved roof thereon;

Fig. 4 is an exploded view in perspective of portions of the side walls and the roof structure in position before being attached.

Fig. 5 is a fragmentary view showing a perspective of a portion of the roof structure and side frame or side plate member to which it is attached;

Fig. 6 is a vertical cross section of a portion of the roof and associated parts;

Fig. 7 is a longitudinal section of a portion of the roof and associated parts;

Figs. 8, 9, 10 and 11 are views similar to Fig. 6, but showing modified forms of the means for attaching the roof to the side plates and side posts; and

Fig. 12 is a section on the line 12—12 of Fig. 1.

In the construction of the conventional railway car, the roof structure is built into the car as the structure is being fabricated. The roof in the

conventional type of car comprises roof sheet or sheets and carlines that are separate and are attached separately with the result that the fabricated structure is heavy, contains an unnecessary amount of material and requires a considerable amount of time and labor in its construction.

The present invention seeks to simplify the construction, lighten the weight, strengthen the structure, and materially reduce the cost of producing the fabricated unit.

Referring now to the drawings, the reference character 1 designates generally a railway car having the under framing 2 supported by the trucks 3, Figs. 1 and 2, the side walls 4, end walls 5, flooring 6, and roof section 7.

In the construction of the car, the end and side walls, together with the corresponding sills and side plates are fabricated separately on horizontal sections by stretching the sheathing and welding together the frame and sheathing, after which these parts are assembled, as will presently appear.

The side wall or outer sheathing 4 of the car 25 comprises a plurality of vertically extending strips or plates of sheet metal 131, see Figs. 1 and 12, welded together in such a manner that the outer surface of the side wall will be smooth. The side posts are made integral with the sheet 30 metal strips, as shown more clearly in Fig. 12. As shown, each sheet 131 except the end sheets, has one edge bent to Z-shape to form a side post 141. The side post 141 is offset inwardly from the body of the sheet 131 as at 138 to form a 35 shallow recess for the reception of the free edge of the adjacent plate. The recess is of such a depth that when the straight edge of the adjacent plate is welded in position in the recess, the outer surfaces will be smooth or flush. The posts 141 are each preferably provided with a reinforcing 40 angle bar 142 which is nested in the inner angle of the side post and is welded thereto.

The upper edge of the sheathing at each side of the car, as well as the upper ends of the side posts 45 141, are rigidly attached to the inner side of the side plate 132, as by being welded thereto. The side plate 132 is angular, being roughly channel form with a downwardly extending flange 135. The channel portion of the plate faces outwardly and is provided with a vertical web portion 160 and with an outwardly extending upper flange 136, as shown more clearly in Fig. 6 of the drawings.

The top end plate 83 to which the end sheath- 50 ing is attached is angular in cross section having

the vertical portion 100, Fig. 7, the horizontal portion 95, seated on the end posts 81, and an outwardly offset vertical portion or flange 110. The upper edge is flanged outwardly as at 110. Suitable gussets of any appropriate form are provided between the vertical portion 100 and horizontal portion 95 of the end plate. In the form of the construction shown, gussets 112 are preferably located above the intermediate end posts 81. These gussets are U-shape in cross section and are triangular in side elevation and have their bases substantially the same width as the horizontal portion 95 of the end plate to which they are rigidly connected as by being welded thereto. The upper end or flange 110 of the end plate extends horizontally over the upper narrow end of the gusset plates and is welded thereto as shown in Fig. 7 of the drawings.

The roof construction comprises a plurality of carlines 162, Figs. 4 and 7, and a roof member 163. The roof member 163 comprises a plurality of sheet metal plates 164, Figs. 1, 4 and 7, that extend transversely of the car and are connected together in a manner similar to the plates forming the outer sheathing at the sides of the car. In the form of the construction shown, however, these plates merely overlap, as shown in Fig. 7. Except at the ends of the car, each plate 164 has one of its side edges bent downwardly, as at 165, and flanged horizontally, as at 300 to form integral carlines angular in cross section as shown in Fig. 7. These roof sheets and integral carlines are so constructed that, when assembled, the roof is cambered on its upper surface.

The depth of the vertical portion 165, Fig. 4, of each carline gradually decreases toward its ends to partially compensate for the cambering of the roof so that the under surfaces of the carlines will be more nearly in a horizontal plane. As a result of this construction, the flange portion 300 of each carline will be considerably widened at its ends, as indicated at 166 in Fig. 7. This widened portion may be partially removed, as shown in Fig. 7, or may be entirely removed, if desired.

The carlines are preferably reinforced by angle bars 167 which rest on the flanges 300 of the carlines and are rigidly connected to both the vertical and horizontal portions of the respective carlines. The carlines are of such length that they are positioned between the vertical portions 160, Fig. 6 of the side plates 132 and are rigidly attached thereto as will presently appear. The sheets 164 extend over the outer flange 136 of the side plates 132 as shown more clearly in Fig. 6 of the drawings and are rigidly attached thereto. The carlines are further secured to the vertical portion 160, Fig. 6 of the side plate by angle bars 168 which extend across beneath the carline and the extension 166 as shown in Fig. 7 and are welded to the lower edge of the carlines and to the web portion 160 of the side plates 132. The plane edges of the roof sheets extend over the adjacent edge of the adjacent roof sheet which forms the integral carline, as shown in Fig. 7, and is welded thereto. If desired, the carlines may be offset slightly so that the plane edge of the adjacent sheet will fit in the recess so as to be flush with the adjacent sheet in the same manner as the sheet forming the side wall and integral side posts described above and shown in Fig. 12.

The front and rear ends of the roof member 163 are extended forwardly and rearwardly over the upper flange 110 of the end plates 83 as shown in Fig. 7, and are welded thereto.

Suitable means are provided for rigidly attaching the side plate 132 to the side wall of the car. As shown in Fig. 6, the upper edges of the side walls or sheathing 4 of the car lap the inner surface of the depending flange 135 of the side plate and are welded thereto. In addition to this, the inner flange 214 of the reinforcing member 142 is extended upwardly alongside the web portion 160 of the side plate 132 and is rigidly connected thereto as by being welded.

In Figs. 8, 9, 10 and 11 are shown modified forms of attaching the roof to the side plate.

In Fig. 8, the inner flange 213 of the side post 141 is extended upwardly alongside the web portion 160 of the side plate 132 and is then bent inwardly to form a bracket for supporting the carline 162 and is rigidly connected to both the carline and the web portion 160 as by being welded thereto.

In Fig. 9, the inner flange 214 of the reinforcing member 142 is extended upwardly along the web portion 160 of the side plate 132 and then bent inwardly beneath the carline 162 and welded as in the previous construction.

In Fig. 10, a separate bracket 215 is employed, the upper end of which is bent inwardly to extend beneath the carline 162 and the body portion of which extends downwardly along the inner surface of the side plate 132 and downwardly along the inner surface of the side post 141 and is welded to the carline; the side plate and the side post for holding the parts in assembled relation.

In Fig. 11, the inner flange 210 of the side post 141 is extended upwardly along the inner face of the web portion 160 of the side plate 132 and is welded thereon. A separate bracket 216, bent to form an angle, has one flange beneath and secured to the carline 162 and its downwardly extending portion is in contact with the web portion 160 and welded thereto.

This is a division of our application Serial No. 133,632 filed on March 29, 1937.

It is thought from the foregoing, taken in connection with the accompanying drawings, that the construction of our device will be apparent to those skilled in the art and that changes in size, shape, proportion or details may be made without departing from the spirit and scope of the appended claims.

What is claimed is:

1. In a railway car having flanged side posts at opposite sides of the car and having side plates supported by said side posts, said side plates each having an outwardly extending flange at its upper edge, a roof unit of sheet metal supported on said side posts, said unit having carlines abutting said side plates at opposite sides of the car and having the sheet metal extending over said flanges and rigidly connected thereto, one flange of each of said side posts extending upwardly across said side plate and bent to extend beneath the adjacent carline and rigidly connected to said plate and carline.

2. In a railway car having side posts at opposite sides of the car each including a web portion extending transversely of the car and a flange extending longitudinally of the car, side plates supported by said side posts, said side plates each having an outwardly extending flange at its upper edge, said side posts each having a vertically disposed angle bar with one flange rigidly connected to the post web and the other flange to the post flange for reinforcing the same, a roof

unit supported on said side posts, said unit comprising roof sheets welded together and having integral carlines abutting said side plates at the sides of the car, said roof sheets extending outwardly over the flanges of said side plates and rigidly connected therewith, said reinforcing bars for said side posts having flange portions ex-

tending upwardly across said side plates and bent to extend beneath said carlines and rigidly connected to said carlines and side plates.

ALFRED C. LOHSE.
